UNITED STATES PATENT OFFICE.

CLARENCE LYMAN PARKER, OF LOS ANGELES, CALIFORNIA.

VARIABLE-PITCH PROPELLER FOR AIRPLANES.

Application filed December 15, 1922. Serial No. 607,116.

To all whom it may concern:

Be it known that I, CLARENCE L. PARKER, a citizen of the United States, residing at Los Angeles, in the county of Los Angeles and State of California, have invented new and useful Improvements in Variable-Pitch Propellers for Airplanes, of which the following is a specification.

My invention relates to a variable pitch propeller which is particularly designed for use on airplanes, and which is in the nature of an improvement on the structure shown and described in Letters Patent No. 1,386,274, issued to me August 2, 1921.

The variable pitch propeller permits a more rapid "get away" as well as permitting the proper adjustment to secure the best results in accordance with the speed at which the machine is traveling, as well as varying atmospheric conditions. It also permits the blade to be thrown into reverse and utilized as an air brake to stop the machine within a very much smaller distance than would be possible with the old type of propeller.

One of the important objects of the present invention is to provide an improved construction by which the propeller blades are connected with the sockets which are secured to the propeller shaft, whereby the same will be firmly wedged therein so as to effectively withstand the powerful centrifugal force developed when the airplane is traveling at great speed, at the same time permitting the free movement of the blades about their axes to vary the pitch thereof.

Another object of the invention is to provide improved means for controlling the variations in pitch from the cock-pit, whereby the aviator may know accurately the position of adjustment and thereby control the action of the airplane accurately at all times.

With the above and other minor objects in view, which will be understood as the description proceeds, the invention consists in certain details of construction which will be described in connection with the accompanying drawings forming a part of this specification.

In the drawings:

Fig. 1 is a side elevation of the forward end of the fuselage showing the propeller.

Fig. 2 is a plan view of the invention connected with a portion of the airplane structure.

Fig. 3 is a side elevation of the operating wheel and dial.

Fig. 4 is a longitudinal section through the forward end of the engine shaft and the propeller.

Fig. 5 is an end view of the propeller 60 blade base before it is applied.

Fig. 6 is a side elevation of the same.

Fig. 7 is an end elevation of the same partly inserted in the ferrule.

Fig. 8 is a side elevation of the same 65 with the ferrule shown in section.

Fig. 9 is a detail perspective view of a taper wedge which is a part of the invention.

Fig. 10 is a longitudinal section at right angles to the plane of Fig. 4. 70

Fig. 11 is an end elevation of a part of the controlling means.

Fig. 12 is a section on the line 12—12 of Fig. 4.

Fig. 13 is a section through the socket and 75 sleeve, taken on the same plane as Fig. 4.

Fig. 14 is a cross section on the line 14—14 of Fig. 10.

Fig. 15 is an end elevation of the parts shown in Fig. 14. 80

Fig. 16 is a section taken through the propeller blade base but showing a modified form.

Fig. 17 is a view similar to Fig. 16 but showing another modification. 85

Fig. 18 is a longitudinal sectional view of the taper wedge as used in the form shown in Fig. 4.

Fig. 19 is a longitudinal section through the rear end of the propeller shaft showing 90 a modified construction.

Fig. 20 is a cross section taken on the line 20—20 of Fig. 19.

Fig. 21 is a view similar to Fig. 19 but showing another modification. 95

Referring more specifically to the drawings, 1 indicates the body or fuselage of an airplane having at its forward end a radiator 2 which may be of the usual construction. On the outside of the airplane body 100 is secured a pair of brackets 3 and 4, preferably by means of bolts which pass through one of the corner beams 6 of the frame. Said brackets form bearings for a longitudinal shaft 5 by the rotation of which the pitch 105 of the propeller blades may be varied through the medium of mechanism which which will be hereinafter described.

The rear end of the shaft 5 is connected by bevel gearing 7, with a stub shaft 8 extending transversely through the beam 6, and provided inside the body with a driven

sprocket wheel 10, which is connected by a sprocket chain 11 with a drive sprocket wheel 12, journaled on a stud 13 formed on a bracket 14 that is secured to a perpendicular post 15 at one side of the cockpit. (Figs. 2 and 3.) The sprocket 12 is of considerably larger diameter than the sprocket 10. Said sprocket 12 is provided with a pair of converging arms 16 and 17 which extend beyond the periphery of the sprocket and constitute a crank in the form of a frame, having at the outer end a handle 18, by means of which the adjusting mechanism may be manipulated. The arms 16 and 17 have secured thereto a brace 19 from which a pointer 20 extends inwardly toward the sprocket over a dial 21 which is fixed to the beam 6 and is provided with indicia to indicate the pitch of the propeller blades which corresponds to the position of the sprocket 12. The dial is of a greater diameter than the sprocket, as shown in Fig. 3, so that the figures on the dial are visible at the side beyond the periphery of the sprocket. The numbers on the dial increase from the zero point in both directions to indicate forward and reverse. By this arrangement, the operating handle and the pointer are both carried by the drive sprocket, and the operator may keep an accurate watch on the movements of the propeller blades through the dial. The mounting of the driving device on the larger sprocket, and the relative arrangement of the pointer and dial, the pointer being carried by the movement of the sprocket, constitutes one of the improvements made over my former patent. Moreover, the mechanism enables the blade to be rotated in either direction, which is not the case with the operating mechanism of my former patent.

The forward portion of the crank shaft 22 is journaled in ball bearings 23 in the forward part of the engine frame 24, as seen in Fig. 4. The crank shaft is preferably made hollow for the sake of lightness, and has its forward end tapered, as at 25, and provided with a key seat 26 for the reception of a spline 27 which is secured to the tapered extremity by means of set screws 28. This provides a seat for the tapered bore of the hub 29, in which the bases of the propeller blades are mounted. Mounted on the shaft 22 is a sleeve 29^a, interposed between the hub 29 and the ball bearings 23, the sleeve being recessed to receive a packing 29^b. On the other side of the ball bearings is a spacing sleeve 29^c which is fitted to the shaft 29.

The tapered end 25 of the shaft has a reduced screw-threaded extremity 30 that receives a hollow nut 31, the head of which is provided with a peripheral flange 32.

Inside the flange 32 and surrounding the

nut 31 is a jamb nut 33 which is threaded into the outer end of the hub 29, as shown at 34. The flange 32 and the head of the jamb nut 33 are preferably provided with slots 35 or similar means for the application of a suitable tool. The outer side of the hub is flattened as shown at 34^a to form a suitable seat for the nuts 31 and 33.

As best shown in Fig. 13, the hub 29 is provided with a number of laterally-extending sockets 36, according to the number of propeller blades to be used, and each socket is provided with an internally threaded outer end 37, which receives the reduced end 38 of a sleeve 39 shown in Fig. 4. The sleeve 39 is provided with an annular shoulder 40 which is adapted to abut against the outer end of the socket 36, and at its outer end the sleeve is reduced as at 41 to receive roller stress bearings 43, an inwardly directed flange 42, which is spaced from the outer end of the sleeve, forming a part of the housing for said bearings. Revolvably mounted in these bearings 43 is the inner reduced end 44 of a ferrule 45, which receives the inner or butt portion of the stem 46 of the propeller blade. The blade at a point removed from the butt end is reduced in width and is formed with an inclined shoulder, and from said shoulder the butt portion begins to increase in width by a gradual taper, thereby defining a butt portion which is substantially dovetail in shape (Fig. 4). At the smaller end of the reduced portion the diameter is four inches, and it increases in diameter to 4 $\frac{1}{8}$ inches, which is the size at the larger end.

In the structure shown in Fig. 4, the intermediate inclined portion or shoulder 47 of the ferrule forms a seat which rests on the shoulder of the butt end of the blade and has openings through which lag screws 48 are inserted obliquely into the stem 46 to furnish additional security in holding the ferrule in place. A ring 49 forms the outer housing for the roller bearings. The ring is preferably formed in sections and rests on the shoulder 47 of the ferrule, and is held in place by the outer end of the sleeve and the joined ends of the ferrule sections. The roller bearing is also retained in place by the same means. This ring is also for holding cup grease in place. Secured to the inner end of the ferrule 45, at the shoulder, is a second ferrule section 50 which increases in diameter toward the axis of the propeller, in accordance with the shape of the butt portion thereof. The inner end 51 of the ferrule section 50 has threaded thereto a collar 52, the outer edge of which forms a seat 53 for roller thrust bearings 54 which bear against a flange 55, formed on the inner end of the sleeve 39. This ferrule section 51, as will be readily

understood, forms an outwardly tapering surface against which the propeller blade base will be firmly engaged to prevent the blade from being displaced when it is rotating at a high rate of speed. As Fig. 4 shows, the outer section of the ferrule extends beyond the shoulder of the blade and embraces the blade for a short distance.

The manner of inserting and securing the propeller in the ferrule will be best understood by reference to Figs. 5 to 8, inclusive. The propeller blade is first cut in the shape shown in Fig. 6, with the inner or butt end flared outwardly. A central tapered hole 56 is bored axially into the end thereof, and radial V-shaped slits 57 are cut from the hole to the outer side and extend from the butt end nearly to the shoulder of the blade, in order to permit the end to be sprung inwardly, as shown in Fig. 8. After the blade base has been inserted into the ferrule, the segments 58 defined by the slits are spread outwardly by the insertion through the hole 56 of a taper wedge 59 which is hollow and has longitudinally tapered fingers 60, Fig. 18, which urge the segments 58 outwardly against the wall of the ferrule. A hollow stem 61, of substantially the same length as the wedge, is then forced into the bore of the wedge 59. The inner portion of the wedge 59 is provided with a rounded reduced end 62 which extends beyond the butt end of the blade and forms a pivot which is rotatably mounted within one of the holes 63 in the hub 29. This is one of the novel features of this invention. Two or more of these holes 63 may be provided, according to the number of propeller blades to be used.

The inner end of the propeller blade base is further secured within the ferrule 50 by the insertion of flat wedges 64 into the slits 57. (Figs. 4, 9 and 12.) The inner end 65 of each of the wedges 64 is reduced in width to correspond with the decrease in the diameter of the ferrule, and the outer edge 66 is thicker than the inner edge to correspond with the greater expansion toward the periphery of the segment. It follows that the wedges 64 are tapered both laterally and longitudinally. This is another novel feature of this invention. The flat wedges are inserted into the slits simultaneously after the ferrule has been applied and after the wedge 59 and the stem have been pressed into place. Glue may, if desired, be applied to the butt and wedges before the latter are pressed into place.

Annular ribs 50^a extend out from the ferrule for strengthening the same, one of the ribs cooperating with flange 42 formed on the sleeve 39 to provide a part of the housing for the stress bearings 43.

Each of the sockets 36 is provided near its base with a peripheral slot 69, and se-

cured to the collar 52 opposite this slot is a plate 67 having upstanding ears 68 to which is pivoted a link 70, the other end of the link being pivoted between the ears 71^a of a link arm 71, which is rigidly secured at its other end to an annular flange 72, formed on a ring 73, supported by ball bearings 74 for rotation, but held against movement longitudinal to the direction of the propeller shaft. (Figs. 10, 11 and 12.) The arm 71 is extended beyond its pivotal connection to form a nose 75, by means of which it is guided in its movement. The intermediate portion of the arm 71 is guided in a slot 76 formed in a bracket 77, which is formed integral with the socket 36. (Fig. 14.) The ball bearings 74 are supported by a bearing ring 78, which is secured to a collar 79 having a square threaded connection 80 with a sleeve 81, which is fixedly secured by means of a flange 82 or other suitable means to the engine frame 24. Figs. 19, 20 and 21 show modifications of this connection. In order that the sleeve 81 may fit up close to the hub of the propeller, the latter is flattened as at 81^a, (Fig. 13). It will be understood that the rotation of the collar 79 will cause the same to move longitudinally of the shaft along the screwthreaded sleeve 81, and thereby rock the propeller blades on their axes to change the pitch thereof. In order to effect this movement, the collar 79 is formed with an integral sprocket wheel 83 which is connected, by means of a sprocket chain 84, to a sprocket wheel 85 on the forward end of a hollow shaft or sleeve 86, (Figs. 1 and 2). This sleeve has a screw-threaded connection 87 with the bracket 3, so that as the sleeve is rotated to advance the collar 79 and sprocket wheel 83 to alter the pitch, the sprocket 85 carried at the forward end of sleeve 86, will also be advanced and will always remain in the same plane with the sprocket wheel 83. The sleeve 86 telescopes the forward end of shaft 5 and has a splined connection 88 therewith. Thus, whenever the sprocket wheel 12 is rotated, a positive and definite movement is transmitted to the propeller blades.

In the modification shown in Fig. 16, instead of the propeller blade base having a bearing in the hub 29, I have inserted in the opening 63 of the hub the reduced circular end 89 of a boss 90, to which is secured a circular plate 91 having at its periphery a wear plate 92 for receiving bearing rollers 93, a cup-shaped housing 94 being secured to the plate 91 by rivets 95 or the like. The inner end 51 of the ferrule is provided with a wearing ring 96, and the inner end of the blade base provides an inner housing for the rollers 93. In this form, the taper wedge 97 may be made in one integral piece, as in my aforesaid patent. This form has

the advantage of providing roller bearings for the propeller blade base at all points at which wear could occur.

In the modification shown in Fig. 17, the boss 98 is secured in one of the openings 63 of the hub 29, and its outer end forms a bearing for the bushing 99, which is secured within a bore at the outer end of the taper wedge 100. In this case, the taper wedge is bored from each end, one bore 101 forming a bearing socket and the other bore 102 being merely for the purpose of reducing the weight. In this form, there is a direct pivotal connection between the wedge and the hub. In both forms shown in Figs. 16 and 17, the flat wedges 64 are employed.

In Figs. 19 and 20, I have shown a form of connection which is especially adapted for an airplane having a rotary engine. In this connection, the propeller shaft 103 is connected by a flange coupling 104 to the shaft of the engine, and between the flange 104 and the hub 29, roller bearings 105 are provided for supporting the propeller shaft within the sleeve 106, the latter being secured by braces 107 from the hood cover 108. The sleeve 106 of this figure is like sleeve 81 of Fig. 4.

The modification shown in Fig. 21 is of the same type as Fig. 4, but shows the threaded sleeve 109 (like sleeve 81) threaded into a flange 110 formed on the forward part of the engine frame 111, and secured in a fixed position of adjustment by means of set screws 112.

From the foregoing description, it will be seen that I have provided a means for connecting the propeller blade base or butt portion to the socket in the hub so that the segments 58 thereof are firmly held both radially and circumferentially, whereby to withstand the centrifugal force developed by the rotation of the propeller. At the same time, the propeller blade is held against lateral stresses by the roller bearings 43, and against end thrust by the roller bearings 53, so that changing of the pitch may be accomplished with the greatest facility regardless of the speed at which the airplane is traveling. The pitch of the propellers may also be quickly read from the dial 21, and the blades may be adjusted for greater speed ahead, or may be adjusted to a reverse position when landing.

I have shown and described the details of what are at present the preferred embodiments of my invention, but it will be understood that various other changes and modifications may be made therein within the scope of what is claimed without departing from the principles of the invention.

What is claimed is:

1. In an airplane, the combination with a fuselage, a propeller shaft and propeller

blades, of a mechanism for varying the pitch of the propeller blades and including a longitudinal shaft on the outside of the fuselage, a rotatable element within the fuselage and operatively connected with said longitudinal shaft for actuating said mechanism, a frame mounted on said rotatable element and carrying an operating handle and a pointer, and a dial mounted in a fixed position concentric with the rotatable element and larger than the same, whereby the pointer will indicate on the dial the degree of pitch of the blades.

2. In an airplane, the combination with a fuselage, a propeller shaft and propeller blades, of a mechanism for varying the pitch of the blades so as to impel the airplane forward or backward at different speeds, including a longitudinal shaft on the outside of the fuselage, a stub shaft geared to the longitudinal shaft and extending through the side of the fuselage and having secured to its inner end a rotatable element for actuating said mechanism, a frame mounted on said rotatable element and extended beyond the periphery thereof, a handle carried by the frame, a pointer also carried by the frame and extending inwardly toward the center of the rotatable element, and a dial of greater diameter than the rotatable element and concentric therewith, so that the figures thereon will show beyond the periphery of said element to indicate the degree of positive or negative pitch of said blades.

3. In an airplane, a propeller having blades capable of being rocked about axes longitudinally of and individual to the blades, a shaft carrying the propeller, mechanism for varying the pitch of the blades including a longitudinal shaft mounted on the outer side of the fuselage, means connecting the shaft to the blades, a drive sprocket on the inside of the fuselage and operatively connected to the longitudinal shaft, a frame mounted on the drive sprocket and carrying an operating handle and a pointer, and a fixed dial concentric with the sprocket and larger than the same, whereby the pointer will indicate the degree of pitch of the blades.

4. In an airplane, a propeller having blades capable of being rocked about axes longitudinally of and individual to the blades, a shaft carrying the propeller, and mechanism for varying the pitch of the blades, said mechanism including a pair of sprocket wheels connected by a sprocket chain, means connecting said sprocket wheels to the blades, the larger of said sprocket wheels being the drive sprocket, a frame mounted on the drive sprocket and carrying an operating handle and a pointer, and a dial mounted in a fixed position at one side of the drive sprocket and larger than the

- same, whereby the pointer will indicate on the dial the degree of pitch of the blades.
5. In an airplane, a propeller having blades capable of being rocked about axes longitudinally of and individual to the blades, a shaft carrying the propeller, and mechanism for varying the pitch of the blades, said mechanism including a drive sprocket, a frame mounted on said sprocket 10 and extended beyond the periphery thereof, a handle carried by the frame, a pointer also carried by the frame and extending inwardly toward the sprocket, and a dial of greater diameter than said sprocket and arranged at 15 one side of the same so that the figures thereon will show beyond the periphery of the sprocket, the pointer moving over the dial face as the sprocket is rotated by grasping said handle.
- 20 6. In an airplane, a propeller having blades capable of being rocked about axes longitudinal of and individual to the blades, a shaft carrying the propeller, a threaded sleeve surrounding the shaft, a collar threaded on the sleeve, means accessible to an operator for rotating the collar about the sleeve, and connections between the collar and the blades and connected to the latter tangentially, said connections including a 25 link and a link arm pivoted thereto, said link arm being extended beyond its pivotal connection to form a nose by which it is guided in its movements.
7. A propeller for airplanes comprising a 30 blade, a ferrule for the butt end of the blade, said blade having a central bore extending inwardly from its butt end, and a wedge entering the bore from the butt end, said wedge having its end projecting from the 35 bore beyond the butt end of the blade and constituting a pivot for the blade.
8. A propeller for airplanes comprising a blade, a ferrule for the butt end of the blade, said blade having a central bore extending 40 inwardly from its butt end, and a wedge entering the bore from the butt end, said wedge being radially expandable and having its end adjacent the butt end of the 45 blade constructed to constitute a pivot for the 50 blade.
9. A propeller for airplanes comprising a blade, a ferrule for the butt end of the blade, said blade having a central bore extending 55 inwardly from the butt end, a hollow wedge having longitudinally tapered fingers entering the bore, and a stem driven into the said wedge to expand the fingers outwardly.
10. A propeller for airplanes comprising a blade, a ferrule for the butt end of the 60 blade, said blade having a central bore extending inwardly from the butt end, a hollow expandable wedge driven into said bore from the butt end, and a stem driven into said hollow wedge.
- 65 11. A propeller for airplanes comprising

a blade, a ferrule for the butt end of the blade, said blade having a central bore extending inwardly from the butt end, a hollow expandable wedge driven into said bore from the butt end, and a stem driven into 70 said hollow wedge, said wedge and said stem being of substantially the same length and the stem being hollow.

12. A propeller for airplanes comprising a blade, a ferrule for the butt end of the 75 blade, said blade having a central bore extending inwardly from the butt end, a hollow expandable wedge driven into said bore from the butt end, and a stem driven into 80 said hollow wedge, both the wedge and the stem being extended beyond the butt end of the blade, and the wedge being constructed to constitute a pivot for the blade.

13. In combination with a hub having a series of openings, a series of propeller 85 blades, each blade being provided with a central wedge having its end projecting from the butt end of the blade and constituting a pivot which is received within one of said openings. 90

14. In combination with a hub having an opening, a propeller blade having a central bore, a wedge fitted in said bore, and means cooperating with said wedge and fitting in said opening to constitute a pivot for the 95 blade.

15. In combination with a hub having an opening, a propeller blade having a central bore, an expandable wedge fitted in said bore, means acting to forcibly expand the wedge, 100 and means located at the butt end of the blade and fitting in said opening to constitute a pivot for the blade.

16. In combination with a propeller blade having its butt end reduced in diameter to define a shoulder, and beyond said shoulder increasing in diameter and flaring outwardly, and a ferrule fitting said butt end and the shoulder, and screws entering the ferrule and the blade at the shoulder thereof. 105

17. In combination with a propeller blade having its butt end provided with a shoulder, and a ferrule fitting said butt end and also formed with a shoulder to fit the shoulder of the blade, and screws passing through 110 holes in the shoulder of the ferrule and entering the blade.

18. In combination with a propeller blade having its butt end provided with a shoulder, a ferrule fitted to the butt end of the 115 blade and the shoulder and formed of two sections detachably connected together at the shoulder.

19. In combination with a propeller blade having its butt end provided with a shoulder, a ferrule fitted to the butt end of the blade and the shoulder and formed of two sections detachably connected together at the shoulder, the outer section extending outwardly along the blade beyond the shoulder. 125 130

20. In combination with a propeller blade having at a point removed from its inner or butt end a shoulder formed by a reduction of the diameter of the blade, and from said shoulder expanding outwardly into a dovetail shape, a ferrule corresponding in shape to the butt portion of the blade and embracing the same including the dovetail portion, the shoulder and that portion of the stem of the blade outwardly from the shoulder, and an axial wedge in said butt end to wedge the same against the ferrule, said wedge having its end adjacent the butt end of the blade constructed to constitute a pivot for the blade.

21. In combination with a propeller blade having its butt end provided with a shoulder, a ferrule fitted to the butt end of the blade and formed of two sections detachably connected at the shoulder, a sleeve embracing the ferrule, and a ball bearing located at the shoulder and held between the outer end of the sleeve and the ferrule where the two sections are joined.

22. In combination with a propeller blade having its butt end provided with a shoulder, a ferrule fitted to the butt end of the blade and formed of two sections detachably connected at the shoulder, a sleeve embracing the ferrule, a ball bearing located at the shoulder and held between the outer end of the sleeve and the ferrule where the two sections are joined, and a ring cooperating with the sleeve and ferrule for holding the ball bearing in place.

23. A propeller for airplanes comprising a blade having its butt end provided with a central bore, and radial slits extending laterally from the bore to the outer side of said butt end, a wedge entering the bore from the butt end, a ferrule for the butt end of the blade, and separate wedges for each radial slit.

24. In a propeller for airplanes, the combination with a ferrule tapered from its inner end toward its outer end, of a propeller blade having its base in said ferrule, said base having a central bore and radial slits, and wedges in said bore and slits, whereby to wedge said base both radially and circumferentially, the wedge in said bore having a bearing surface on which the blade is rotatable to vary the pitch.

25. A propeller for airplanes comprising a blade, a ferrule for the butt end of the blade, said butt end having a central bore and radial V-shaped slits extending in-

wardly from the end; a central wedge entering the bore from the butt end to expand the butt toward the ferrule, and flat wedges 60 entering the slits around the central wedge to expand the butt circumferentially, said flat wedges being tapered both laterally and longitudinally.

26. A propeller for airplanes comprising 65 a blade, a ferrule for the butt end of the blade, said butt end having a central bore and radial slits extending inwardly from the butt end, a round tapered wedge entering the bore from the butt end to expand 70 the butt toward the ferrule, and flat wedges entering the slits to expand the butt circumferentially.

27. A propeller for airplanes comprising 75 a blade, a ferrule for the butt end of the blade, said ferrule and butt end being tapered from their inner extremity toward the top of the blade, said butt end having a central bore and radial slits extending inwardly from the butt end, a round tapered 80 wedge entering the bore from the butt end to expand the butt toward the ferrule, and flat wedges entering the slits to expand the butt circumferentially, the flat wedges being tapered both laterally and longitudinally. 85

28. A propeller for airplanes comprising 90 a blade, a ferrule for the butt end of the blade, said butt end having a central bore and radial slits extending inwardly from the end, a round tapered longitudinally 95 slotted wedge entering the base from the butt end to expand the butt toward the ferrule, a cylindrical core for said wedge, said wedge and core forming a bearing for the inner end of the blade butt, and flat wedges 95 entering the slits to expand the butt circumferentially.

29. A propeller for airplanes comprising 100 a blade, a ferrule for the butt end of the blade, said ferrule and butt end being tapered from their inner extremity toward the tip of the blade, said butt end having a central bore and radial slits extending inwardly from the end, a round tapered wedge 105 entering the bore from the butt end to expand the butt toward the ferrule, said wedge forming a bearing for the inner end of the blade butt, and flat wedges entering the slits to expand the butt end circumferentially.

In testimony, that I claim the foregoing 110 as my own, I have hereto affixed my signature.

CLARENCE LYMAN PARKER.
